UNITED STATES PATENT OFFICE.

ROBERT HENRY ELLIS AND FRANK SIMPER, OF FREMANTLE, WESTERN AUSTRALIA,
AUSTRALIA.

PACKING CASE.

Application filed September 11, 1922. Serial No. 587,536.

To all whom it may concern:

Be it known that we, ROBERT HENRY ELLIS and FRANK SIMPER, both subjects of the King of Great Britain, residing at South 5 Street, Fremantle, Western Australia, Commonwealth of Australia, have invented certain new and useful Improvements in Packing Cases, of which the following is a specification.

This invention provides a packing case for the holding and carriage of goods and merchandise whose construction enables it to be unbreakable and non-pillageable without detection, and capable of resisting great 15 strain and hard usage. In this invention each of the side walls of the case is of identically the same form of construction and said case is thereby capable of being standardized and consequently manufactured with 20 economy. A chief structural advantage resides in the wall members being relieved of any strain or undue pressure as all thrust and strain both in an inward and outward direction is received by the body frame members 25 which act as fenders or protectors for the case and its contents as a whole. These and other structural features will now be explained with the aid of the attached drawings wherein Fig. 1 is a perspective view 30 of a packing case made in accord with our invention. Fig. 2. is a perspective corner view of a structural modification in which the body frame members are made of a scarfed joint type. Fig. 3. is a similar view 35 of another structural modification showing the body frame members made of a plain joint type. Fig. 4. is a perspective under plan view showing the employment of a metal strap plate or rod for reinforcing the 40 wall plates together.

Referring to Fig. 1. wherein the case is shown as comprised of the companion vertical side body frame members as *a* and *a'* and of the horizontal companion and end 45 body frame members as *b* and *b'* and of the companion top and bottom frame members as *c* and *c'*.

To said body frame members are mutually secured the side wall members *a*, the end 50 wall members *b* and the top and bottom wall members *c*. These respective wall members are positioned and held flush on their inside faces, this avoiding any objectionable projections and resultant loss of 55 internal space. These respective body frame

members are all secured to each other by nails *c* in a mutual and interlocking manner and are so arranged and positioned as regards each other that they function as fenders or protectors for the case and its 60 contents as a whole from any external force or pressure and also receive any outwardly directed force or pressure which may originate from the contents of the case—thus 65 relieving the wall members from said outwardly directed force or pressure.

Referring to the structural modification shown in Fig. 2. the body frame members as *d*—*e* and *f* are each scarfed or made with the set off *g* to therein mutually receive the 70 ends of their companion members as shown and to be thereat secured by nails *n*.

The ends of said members *d*—*e* and *f* are arranged and positioned flush with each other as shown. 75

In this modified type of construction the filling or wall boards (not shown) are adapted to be loosely and internally placed in position and made to lie against the members *d*—*e* and *f* or they may be nailed there- 80 to if desired.

Referring to the further structural modification shown in Fig. 3. the body frame members as *j*—*k* and *m* are secured to each other as shown by the nails *y* and their respective face edges being made flush with each other as in a plain joint manner. In this latter construction the filling or wall boards (not shown) are adapted to be loosely and internally placed or nailed to the members *j*—*k* and *m* or to be nailed externally thereto if desired but we prefer the internal 90 method of positioning said wall members.

Referring to Fig. 4. the wall boards as above mentioned and referred to are reinforced and stayed to each other by the flat straps as *p* in a mutual and companionwise manner. 95

The frame members adjacent their ends are inset transversely thereof to receive the 100 straps and in a similar manner the side members are complementally inset to receive the straps as shown at *q* Figure 1.

What we claim as our invention and desire to obtain by Letters Patent is:— 105

A packing case comprising frame members, wall members and straps; said frame members extending across the outside of the ends of wall members on all sides of the case and being inset adjacent their ends, said 110

frame members holding the wall members against the edges of frame members on adjacent sides, said straps running parallel with said frame members on the opposite sides of said wall members and lying in the insets in the ends of the frame members.

In testimony whereof we have hereunto

set our hands in presence of two subscribing witnesses.

ROBERT HENRY ELLIS.
FRANK SIMPER.
